CLAIM

The ornamental design for a deck box, as shown and described.

DESCRIPTION

FIG. 1 is a perspective view of the deck box in an open configuration;

FIG. 2 is a perspective view of the deck box in a closed configuration;

FIG. 3 is a front elevation view of the deck box in an open configuration;

FIG. 4 is a front elevation view of the deck box in a closed configuration;

FIG. 5 is a right side elevation view of the deck box in an open configuration;

FIG. 6 is a right side elevation view of the deck box in a closed configuration;

FIG. 7 is a left side elevation view of the deck box in an open configuration;

FIG. 8 is a left side elevation view of the deck box in a closed configuration;

FIG. 9 is a rear elevation view of the deck box in an open configuration;

FIG. 10 is a rear elevation view of the deck box in a closed configuration;

FIG. 11 is a bottom plan view of the deck box; and,

FIG. 12 is a top plan view of the deck box.

The broken lines in FIGS. 3-11 depict portions of the deck box that form no part of the claimed design.

1 Claim, 7 Drawing Sheets
